INVENTOR
ALLAN C. RUSH

by Townsend Bros
Attny.

UNITED STATES PATENT OFFICE.

ALLAN C. RUSH, OF LOS ANGELES, CALIFORNIA.

INJECTOR-BURNER.

SPECIFICATION forming part of Letters Patent No. 784,505, dated March 7, 1905.

Application filed December 7, 1903. Serial No. 184,122.

To all whom it may concern:

Be it known that I, ALLAN C. RUSH, a citizen of the United States, residing at Los Angeles, in the county of Los Angeles and State 5 of California, have invented certain new and useful Improvements in Injector-Burners, of which the following is a specification.

This invention relates to positive and extremely efficient means for utilizing liquid 10 hydrocarbons as fuel.

The primary object of the invention is to provide a burner which, while extremely durable, shall be very positive and efficient in operation and in which all liability of clogging 15 or choking the burner by carbonization will be avoided and which shall be particularly adapted for use with crude hydrocarbon oils—such, for instance, as the heavy crude asphaltum oils of California.

20 A further object of the invention is to provide a burner which is adapted to furnish a sheet of flame either circular in form or in any desired arc of a circle and in which the body of the flame may be of any desired depth, 25 according to the requirements of the particular apparatus with which it is used, so that the burner-body may with very slight expense, either of time, attention, or material, be readily adapted for various uses, from that in 30 which a circular flame is desired to that in which a flame is desired to be projected in a given direction or arc of a circle and in which the body of the flame may be regulated at will.

35 A further object of the invention is to provide suitable means by which the amount of flame generated by the burner may be entirely within the control of the operator and the area thereof may be positively and readily 40 regulated by the operator from without the fire-box, as desired.

Other objects and ends in view will herein-after appear from the detail description of construction and operation.

45 To these ends the invention consists, primarily, in a body having an annular channel, the outward wall of which terminates in a plane, and I provide means for supplying liquid fuel to said channel, means for direct- 50 ing an expansive fluid from the interior out-

ward radially across said channel in a plane parallel to said terminal plane, so that when the channel is unobstructed a circular flame may be produced and by temporarily closing a portion of the channel a fan-shaped blaze 55 may be produced; also, in providing means whereby the operator from outside the fire-box may readily regulate the depth of the flame.

The invention consists, further, in the provision of an air-chamber surrounding the oil-pipe and extending outside the furnace and communicating air to the burning liquid fuel at the point of projection thereof into the fire-box, the air-chamber serving not only to supply atmospheric air to the burning vapor, but also as a means to prevent too great super-heating of the oil in the oil-pipe; also, in the provision of means whereby the amount of air supplied by said chamber may be controlled and the delivery thereof regulated as desired.

The invention consists, further, in various constructions and in general and specific combinations of parts, all as hereinafter described, 75 and particularly pointed out in the claims, and will be more readily understood by reference to the accompanying drawings, forming a part of this specification, and in which—

Figure I is a side elevation of an injector-burner embodying my invention. Fig. II is a longitudinal sectional view of the burner with the steam and oil supply regulating apparatus omitted. Fig. III is a perspective view of a segmental ring which I employ when 80 it is desired to close a portion of the annular channel and to project the flange from only a portion of the periphery of the burner. Fig. IV is a perspective view of the deflector. Fig. V is a plan view on line V V of Fig. II, with 85 the hollow plug forming the extended steam-way removed. Fig. VI is a fragmental perspective view of the hollow plug. Fig. VII is a side elevation similar to Fig. I, showing my burner equipped with additional regulat- 90 ing apparatus. Fig. VIII is a longitudinal sectional view showing the burner equipped with the regulating apparatus of Fig. VII, the steam and oil supply regulating apparatus being omitted. Fig. IX is a plan with the 100

cap and the sleeve-operating rod removed. Fig. X is a view of the two-part segmental ring, the operating-rod therefor being shown in section. Fig. XI is a sectional plan view on the line XI XI of Fig. VII. Fig. XII is a transverse sectional view on the line XII XII of Fig. XI. Fig. XIII is an end view of the rear end of the apparatus, as shown in Fig. XI. Fig. XIV is a partial front view in perspective of my burner. Fig. XV is a longitudinal sectional view of the steam-strainer which I employ. Fig. XVI is a longitudinal sectional view of my three-way coupling for the oil-pipe and the packing-gland I employ about the steam-pipe passing through the coupling.

As shown in the drawings, 2 designates the atomizer-body, which is preferably in the form of an L and hollow and into one end of which 20 screws the oil-pipe 3. The body 2 is cored out to provide the two chambers 4 and 5, which are respectively for the oil and steam, the chamber 4 surrounding the chamber 5. The steam-pipe 6 screws into the ends of the wall of the chamber 5, the pipe 6 being within the pipe 3. The body 2 is preferably cast with a top plate 7 integral therewith. This plate 7 is provided with a central opening through which the lower end of hollow plug 8 passes to screw 25 into the top end of the wall of the chamber 5. The top plate 7 is also cut away to form a curved or arc-shaped passage or duct 9, forming the outlet from the chamber 4.

The hollow plug 8 is provided with a shoulder 10, adapted to seat on a seat 11 on the top plate. The hollow plug 8 is provided with one or more peripheral ducts or outlets 12, leading from the chamber of the plug above the top plate 7 and horizontally across the 40 plane of the oil-outlet 9.

13 represents a segmental ring provided on its under side with a bead 14, adapted to rest in the duct 9 and in a groove or channel 15, formed in the top plate. The cut-away portion of this segmental ring determines the width or arc of the flame projected by the burning intermingled steam and liquid fuel.

16 represents a sleeve adapted to be screwed onto the upper threaded end or shank of the 50 hollow plug, as shown. This sleeve is hollowed out at its lower end to form a central chamber, the inner end of the chamber being of sufficient diameter to permit the sleeve 16 to be screwed down, so that the lower end of 55 the sleeve 16 comes below the plane of the bottom of the port or ports 12. A suitable expansion-chamber 17 is formed within the lower end of the sleeve 16 by increasing the diameter of the central chamber of the sleeve, 60 as shown. It is thus seen that the outlet of steam from the chamber of the hollow plug is through the port or ports 12 into the expansion-chamber 17 and thence out through the annular duct or passage 17', formed between 65 the lower edge of the sleeve 16 and the upper

face of the top plate 7. In order to provide means whereby the flow of steam from the chamber of the plug 8 into the expansion-chamber 17 may be regulated to agree with the regulation of the segmental ring 13, I 70 provide a secondary segmental ring 19, adapted to seat upon the top face of the top plate 7 and provided with a vertical flange adapted to extend into and close that portion of the expansion-chamber 17 which it is desired to 75 cut out of service.

20 is a deflector which, as shown best in Fig. IV, is in the form of a sleeve adapted to be slipped over the sleeve 16 and provided with a horizontal flange 21. The flange 21 is provided with a series of holes 22, through which bolts 23 pass into the rim of the body 2, holding the sleeve 20 in place on the body 2. As shown in Fig. II, the bolts 23 also pass through the segmental ring 13, thereby holding the 80 ring 13 fixed in place. The outer periphery of the upper end of the sleeve 20 is threaded and adapted to receive the cap or cover 24, adapted to be screwed into place thereon. As shown in Fig. II, the sleeve 16 is held in the 85 desired position over the hollow plug 8 by a lock-nut 25.

The body 2 is provided with an opening in its wall leading into the chamber 4, through which access may be had to the chamber 4 for 90 the purpose of cleaning the same when desired. This opening is normally closed by a plug 26.

In Figs. VII to XIII of the drawings I have shown my burner provided with means 100 whereby the width of the flame, as well as the thickness of the body of the flame, may be regulated at will by the operator from outside the fire-box or furnace in which the burner is used. In order to accomplish these results, I 105 make the segmental regulating-ring in two parts 13^a 13^b. The part 13^a is cut away so as to provide a horizontal flange 13^c, having on its under face a series of teeth 13^d, and the part 13^b is cut away, as shown, and provided 110 on the upper face of the horizontal flange 13^c, formed by the cutaway, with a series of teeth 13^e. The flanges 13^c and 13^e, as shown, extend one above the other. The two parts or segments 13^a 13^b, forming the segmental regulating-ring, in this form of my burner are 115 adapted to be revolved, so as to increase or decrease the free or unobstructed portions of the channel 9 and steam-discharge slot 17', formed between the upper faces of the top 120 plate 7 and the edge of the sleeve 16. As the beads 14 of the segments 13^a 13^b extend into the channel 9 and the parts 13^a and 13^b operate to shut off the exit of steam through the steam-discharge slot 17', it is obvious that the 125 movement of the two parts or segments 13^a 13^b toward and away from each other regulates the portions or lengths of the oil-duct and steam-discharge slot 17', through which oil and steam may be emitted, and by such 130

movement of these segments or parts the lateral adjustment of the width of the flame is effectuated.

27 represents a rod which forms the means extending from within the reach of the operator outside the fire-box or furnace into connection with my burner and by which the movement of the segments 13^a 13^b is controlled. As shown, the body 2 of the burner 10 is provided with a vertical flange 28, through an opening in which the rod 27 extends.

29 represents a plug in said opening adapted to take up any wear.

The inner end of the rod 27 is in the form 15 of a bevel-gear 30 and meshes with the teeth 13^a and 13^b of the segments 13^a 13^b, respectively. By rotating the rod 27 the desired movement of the segments 13^a 13^b is accomplished. The rod 27 has a bearing in the 20 standard 31, provided by a vertical flange rising from the body of the burner. The other end of the rod 27 has a bearing in the standard 32 outside the fire-box or furnace, this standard 32 being either formed integral with 25 the pipe 3 or in any other desired manner. After passing through its bearing in the standard 32 the rod 27 passes through a gage plate or dial 33, which may be formed separate or integral with the standard 32, as desired.

30 On the outer end of the rod 27 I provide an operating or hand wheel 34, by means of which the rod 27 may be revolved, and in connection with such hand-wheel an indicator or pointer 35, operating in connection with the 35 dial 33.

To provide the means whereby the vertical depth or volume of the flame may be regulated by the operator or attendant from without the fire-box or furnace, the sleeve 16 is 40 provided on its periphery with gear-teeth 36. As shown in Fig. VIII, these teeth only extend down the periphery of the sleeve 16 far enough to permit the desired range of regulation. An operating-rod 37 has on its inner 45 end a worm 38, which meshes with the external gear of the sleeve 16. This rod 37 also has bearings in the standards 31 and 32 and is provided with an operating or hand wheel 39, pointer 40, and dial 41, similar to the operating-wheel, pointer, and dial provided in 50 connection with the rod 27.

When my burner is provided with means for adjusting the sleeve 16 vertically from without the fire-pot or furnace instead of the 55 cap 24, as shown in Fig. II, I provide a cap 42, having a chamber into which the upper end of the sleeve 16 extends and through the top of which the end or shank of the plug extends.

60 The flange 44 of the cap rests upon the rim of the standard 28.

In order to supply the requisite atmospheric air from outside the fire-box or furnace to the burning fuel, I surround the pipe 3 with an 65 air pipe or cylinder 45, which, as shown, is

preferably open to deliver air only below the injected burning fuel and in front of the burner. This pipe or cylinder extends outside the fire-box or furnace and has its under end flared in order to secure a better suction 70 of air into the fire-box.

When my burner is used with the regulating means shown in Figs. VII to XIII, the secondary segmental or closure ring 19 is made of a sufficiently large segment to fully cover 75 or close any space or opening which may be left between the ends of the flanges 13^c 13^e of the parts or segments 13^a 13^b of the segmental regulating-ring, so that there is no possibility of either oil or steam being emitted at 80 the rear of the burner. This closure-ring 19, as shown, is provided with a vertical flange at its inner periphery. As this flange extends up into the cavity of the steam-gage it prevents any steam from escaping backward when 85 the steam-gage or sleeve 16 is raised or lowered to adjust or regulate the width of the steam outlet or discharge 17.

In Figs. I and VII, I have shown the steam and oil connections and supplying-pipes. 47 90 represents a four-way connection, into one way of which the oil-pipe 3 is screwed. The oil-supply pipe 48 enters the connection 47 from the bottom way. The steam-supply pipe 49 is connected with the upper way of this connection 47 and through pipes 50 and 51, union 52, L 53, collar 54, and the reducing-plug 55, with the pipe 6 projecting through the way opposite the pipe 3. The pipes 50 and 51 are connected by the valve 55', which, as shown, 95 is preferably provided in connection with the wheel 57 on the valve-stem 58, the wheel 57 being graduated, as shown.

A valve 59 is interposed in the pipe 49, by which the passage of steam through the nipple 60, connected with coupling 47 and open into the pipe 3, is controlled, thus forming means whereby steam may be blown through the pipe 3 to clean out the chamber 4 and duct or outlet 9, if desired. The connection of the 105 nipple 54 with the plug 55 is shown best in Fig. XVI, in which it is seen that the opening or way through the connection 47 opposite the pipe 3 is of a diameter just sufficient for the steam-pipe 6 and that a packing-gland 110 61 is provided, into which packing 62 is forced about the pipe 6, a washer 63 about the pipe separating the inner and outer layers of packing, being held in place by the reducing-plug 55, as shown. The end of the pipe 6 screws 115 into the collar 54.

In the steam-supply pipe 49, between the source of supply and the three-way connection 64, I interpose a steam-strainer, the construction of which is shown in detail in Fig. XV, 125 where it will be seen that the pipe 49 is connected with its continuation 49' by a union 65, preferably provided with a handle, whereby it may be turned. The chamber 66 is of slightly greater diameter than the diameter 130

of the pipe 49', which, as shown, is provided with an annular flange 67, between which and the shoulder 68 a gasket (not shown) may be employed to insure a steam-tight joint. The 5 strainer 69 is preferably of brass and with a dome top and slotted sides, the base-flange 70 being seated on the flange 67 of the pipe 49'. The end of the pipe 49 bears against the top 10 face of this flange 70. The end of the pipe 49' preferably extends upward beyond the top of the flange 67 and into the bottom flange 70 of the strainer.

The operation is as follows: The valve 55' is operated to permit the passage of steam 15 from the steam-supply pipe through the steam-pipe 6 and to permit it to flow out through the ports 12 into the expansion-chamber 17 and thence through the steam-discharge slot 17'. By terminating the sleeve between the 20 outer channel or duct 9 and the expansive-fluid supply the expansive fluid is allowed to begin to expand upward and away from the face of the top plate 7 before reaching the oil. This avoids excessive expansion of the expansive 25 fluid against the body of oil in the channel or duct 9, so that the effect is more to suck off the surface of the oil as it rises in the channel, thereby in a measure vaporizing the oil from the outlet. The hollow stem being provided 30 with radial ports 12 directs the expansive fluid against the inner wall of the expansion-chamber or inner channel 17. The expansive fluid expands in this channel and is evenly distributed therein, so as to pass out evenly 35 throughout all portions of the fluid-outlet 17'. By constructing the top plate 7 with a plane flat face of considerable width between the channel or duct 9 and the channel or expansion-chamber 17' and providing the sleeve 16 above the said 40 face and terminating the outer periphery of the sleeve well within the surface of the said flat face an adjustable discharge-slot for the expansive fluid is provided, and the expansive fluid is directed across the outer channel or 45 duct 9 in a plane parallel with the plane of the outer rim 2' of the body 2. By vertical adjustment of the sleeve 16 on the screw-threaded stem of the plug 8 the width of the slot 17' may be regulated as desired. After the valve 50 55' has been opened the valve in the oil-pipe 48 is opened and the supply of oil turned on. The oil rising up through the oil-pipe 3, chamber 4, into the channel or duct 9 is carried out therefrom by the sheet of expansive fluid 55 flowing across in a plane thereabove.

The flame produced by this burner may be readily regulated as desired and a very long narrow flame secured or a very wide flame with short projections. By suitably regulating the 60 sleeve 16 the vertical body or depth of the flame may be regulated to suit the particular conditions under which the burner is used, and I have found that with this burner it is possible to secure a narrow short or very 65 thick flame resembling more a ball of fire

than the ordinary blast-flame secured by the majority of injector-burners. With the construction shown and described I am able to avoid all carbonization on the burner and all tendency to clog with any of the minerals or 70 impurities contained in the oil.

The air-pipe or cylinder 45, as shown, opens at the front end and below the flame, and the heat of the burning atomizing-oil causes a suction through the pipe 45 and supplies the 75 flame with the needed oxygen. 71 represents a flanged set-collar which I provide upon the pipe 3 beyond the flaring end of the pipe or cylinder 45. The flange 72 of this collar is of sufficient diameter so that by moving this 80 collar into proximity with the end of the pipe 45 or away therefrom the entrance of air into and the passage of air through the pipe 45 may be regulated as desired to secure the supply of requisite oxygen to the burning atomizing liquid fuel. The air-chamber provided by the pipe or cylinder 45 surrounding the oil-pipe 3 prevents the furnace heat effectuating the carbonization of the oil in the oil-pipe 3 and prevents the heating of the oil to 90 too great a degree. It is thus seen that I utilize the heat of the steam for superheating the oil and utilize the air passing through the cylinder 45 to prevent the furnace heat from heating the oil too hot. 95

If desired, the segmental ring 13 may be removed, and a circular flame will then be produced.

What I claim is—

1. A body having two curved or arc-shaped 100 channels, means for supplying liquid fuel to the outer channel, means for supplying an expansive fluid to the inner channel, adjustable closure means for adjusting the length of the exit-outlets through said inner and outer 105 channels and to limit the space across which the expansive fluid will pass, and operating means extending to within the reach of the operator for adjusting said first-named means while the burner is in operation. 110

2. A body having two curved or arc-shaped channels, means for supplying liquid fuel to the outer channel, means for supplying an expansive fluid to the inner channel, adjustable means operatively positioned with respect to the inner channel and for regulating the vertical width of the outlet from said inner channel, an adjustable director arranged to close a portion of the outer channel and to limit the space across which the expansive 120 fluid will pass, and means extending to within the reach of the operator for operating said adjustable means to regulate the vertical width of the expansive-medium-discharge slot or outlet. 115

3. A body having two curved or arc-shaped channels, means for supplying liquid fuel to the outer channel, means for supplying expansive fluid to the inner channel, adjustable means operatively positioned with respect to 130

and for closing a portion of the outer channel and limiting the space across which the expansive fluid will pass, adjustable means operatively positioned with respect to the inner channel and for regulating the width of the outlet from said inner channel, and means extending from said body to within reach of the operator for operating said adjustable means.

4. An atomizer comprising a body having an upwardly-opening curved or arc-shaped channel, means for supplying liquid fuel to said channel, means for directing an expansive material outward radially across said channel above the same, detachable closure means for regulating the length of the portions of said channel from which liquid fuel may be emitted and across which expansive material may flow, and means whereby said detachable means may be adjusted to regulate the closure of said channel and the flow of expansive material across the same.

5. An atomizer comprising a body having an upwardly-opening curved or arc-shaped channel, means for supplying liquid fuel to said channel, means for directing an expansive material outwardly radially across the same, detachable means for closing a portion of said channel, and means for adjusting said detachable means to regulate the lateral closure of said channel and means for regulating the vertical width of the expansive-medium stream.

6. An atomizer comprising a body having an upwardly-opening channel, means for supplying liquid fuel to said channel, means for directing an expansive material outward radially across said channel above the same, detachable means for closing a portion of said channel, regulable means operatively positioned with respect to the expansive-medium discharge, and means extending out from said atomizer, for operating said last-named means to regulate the vertical width of the expansive-medium discharge.

7. An atomizer comprising a body having an upwardly-opening curved or arc-shaped channel, means for supplying liquid fuel thereto, means for directing an expansive material outward radially across the channel above the same, detachable means for closing a portion of said channel, regulable means operatively positioned with respect to the expansive-medium discharge, means extending out from said atomizer, for operating said last-named means to regulate the vertical width of the expansive-medium discharge, and means provided above said annular channel and spaced apart therefrom, for controlling the upward expansion of the expansive material as it flows radially across said channel.

8. An atomizer comprising a body having an upwardly-opening curved or arc-shaped channel, means for supplying liquid fuel thereto, means for directing an expansive material outward radially across the channel above the same, detachable means for closing a portion

of said channel, regulable operating means for adjusting said detachable means, and means, provided above said annular channel and spaced apart therefrom, permitting the expansive material to expand upwardly as it flows radially across said channel.

9. A body having two curved or arc-shaped channels, means for supplying liquid fuel to the outer channel, means for supplying an expansive material to the inner channel, adjustable means arranged to close a portion of the outer channel and to limit the space across which the expansive material will pass, operating means extending out from said body to within the reach of the operator for adjusting said adjustable means while the burner is in operation, and means provided above the outer channel and spaced apart therefrom, permitting the expansive material to expand away from said outer channel as it flows thereacross.

10. A body having two curved or arc-shaped channels, means for supplying liquid fuel to the outer channel and an expansive material to the inner channel, means for closing a portion of the outer channel and to limit the space across which expansive material will flow, regulable means operatively positioned with respect to the expansive-medium discharge, means extending out from said atomizer to within reach of the operator, for operating said regulable means to vary the vertical width of discharge from said inner channel, and means, provided above the outer channel spaced apart therefrom, permitting the expansive material to expand away from said outer channel as it flows thereacross.

11. A body having two curved or arc-shaped channels and between said channels a flat face of considerable width, means for supplying liquid fuel to the outer channel, means for supplying expansive material to the inner channel, adjustably-arranged means above said inner channel extending across a portion of said flat face and terminating in a direction giving edge forming in connection with said face, a slot to direct the expansive material across the outer channel, and means extending out from said body for operating said adjustably-arranged means to vary the width of said expansive-material slot.

12. A body having two curved or arc-shaped channels and between said channels a flat face of considerable width, means for supplying liquid fuel to the outer channel, means for supplying an expansive material to the inner channel, adjustably-arranged means above said inner channel extending across a portion of said flat face and terminating in a direction giving edge forming in connection with said face, a slot to direct the expansive material across the outer channel, means extending out from said body for operating said adjustably-arranged means to vary the width of said expansive-material slot, and means provided above the outer channel and spaced apart therefrom,

for controlling the upward expansion of the expansive material as it flows across the outer channel.

13. A body having two curved or arc-shaped channels and between said channels a flat face, means for supplying liquid fuel to the outer channel, means for supplying an expansive fluid to the inner channel, means above said inner channel extending across a portion of said flat face to form therewith a slot to direct the expansive fluid across said outer channel, said means embracing an expansion-chamber, regulable means for closing said outer channel and said expansive-medium-discharge slot, 15 means for operating said regulable means to vary the opening from said channel and slot.

14. A body having a curved or arc-shaped channel, means for supplying liquid fuel to said channel, means for directing an expansive fluid across said channel, a two-part segmental member having a bead to fit a portion of said channel and to limit the space across which the expansive fluid may pass, and means for moving the parts of said segmental member to vary the space across which the expansive fluid may pass.

15. A body having a curved or arc-shaped channel, the outer wall of which terminates in a plane surface, means for supplying liquid fuel to said channel, means for directing an expansive fluid outward radially of said channel in a plane parallel to said terminal plane, a two-part segmental member having a bead to fit a portion of said channel and to limit 30 the space across which the expansive fluid may pass, and means for moving the parts of said segmental member to vary said space.

16. A body having two curved or arc-shaped channels, a hollow stem projecting upward 40 therefrom and closed at the top and provided with openings leading into the inner channel, means for supplying liquid fuel to the outward channel, means for supplying an expansive fluid to the hollow stem, a deflector adjustably mounted on the hollow stem, a two-part segmental member, closing a portion of the outer channel, and means extending from said body to within reach of the operator for moving said parts of said segmental member in relation to each other to vary the discharge of 45 expansive fluid across said channel.

17. An atomizer comprising a body having two discharge-slots, means for supplying oil through one of said slots, means for supplying 55 expansive material through the other slot or duct, said slots being so arranged that the fuel and fluid material intermingle outside said slots, adjustable means for regulating the opening through said slots, and means extending 60 from said atomizer to within the reach of the operator whereby said closing means may be operated to simultaneously vary the discharge from both said slots as desired.

18. An atomizer comprising a body having 65 a curved or arc-shaped channel, means for

supplying liquid fuel thereto, a hollow plug, means for supplying expansive fluid thereto, a sleeve adjustably mounted with relation to said plug and provided with a chamber at its lower end into which expansive fluid is communicated through ports in said plug, said body provided with a flat face between which and the lower end of said sleeve is formed an expansive-fluid-discharge slot adapted to discharge fluid across said annular channel, and means extending from said atomizer to within reach of the operator whereby said sleeve may be adjusted vertically to vary the width of said fluid-discharge slot.

19. An atomizer comprising a body having a curved or arc-shaped channel, means for supplying liquid fuel thereto, a hollow plug, means for supplying expansive fluid thereto, a sleeve adjustably mounted with relation to said plug and provided with a chamber at its lower end into which expansive fluid is communicated through ports in said plug, said body provided with a flat face between which and the lower edge of said sleeve is formed an expansive-fluid-discharge slot adapted to discharge fluid across said annular channel, 85 said sleeve provided upon its periphery with gear-teeth, and an operating-rod extending from within reach of the operator into said atomizer, and provided at its inner end with a worm meshing with said teeth.

20. An atomizer comprising a body having a curved or arc-shaped channel and a plane face outside said channel, a hollow plug closed at its top and provided with a radial outlet, 100 a member forming a chamber about said plug and into which the same communicates, a plane face being provided between the outer channel and said plug, said plane face lying in a plane higher than the plane of the outer 105 plane face, the end of said member being spaced apart from said inner plane face to provide a discharge-slot, means for supplying liquid fuel to the outer channel, and means for supplying an expansive fluid to said plug.

21. An atomizer comprising a body having a curved or arc-shaped channel and a plane face outside said channel, a hollow plug closed at its top and provided with a radial outlet, a member forming a chamber about said plug and 115 into which the same communicates, a plane face being provided between the outer channel and said plug, said plane face lying in a plane higher than the plane of the outer plane face, the end of said member being spaced apart from said inner plane face to provide a discharge-slot, means for supplying liquid fuel to the outer channel, means for supplying an expansive fluid to said plug, and means extending out from said atomizer and operatively connected with said member for raising and lowering said member.

22. An atomizer comprising a body having a curved or arc-shaped channel and a plane face outside said channel, and a plane face inside 130

said channel, said inside plane face being higher than the rim of the outside plane face, means for supplying liquid fuel to said channel, means for discharging expansive fluid over said inside plane face and across and above said annular channel, adjustable means for closing said outer channel, and means for operating said adjustable means to vary the width of the discharge.

23. An atomizer comprising a body having a curved or arc-shaped channel and a plane face outside said channel, and a plane face inside said channel higher than the outside plane face, means for supplying liquid fuel to said channel, means for discharging expansive fluid over said inner plane face and across and above said channel, regulable means for closing said outer channel and for cutting off the discharge of expansive fluid over the corresponding portion of said inner face, and means for operating said regulable means.

24. An atomizer comprising a body having a curved or arc-shaped channel and a plane face outside said channel, and a higher plane face inside said channel, a hollow plug extending up inside said inner plane face and provided with a radial port thereabove, an adjustable member surrounding said hollow plug and provided with an expansion-chamber into which said plug communicates, the lower end of said member spaced apart from said face and provided with a discharge-slot from said expansion-chamber over said inner face, regulable means closing said outer channel and said expansive-medium discharge-slot, and means for operating said regulable means.

25. An atomizer-body having a channel in its top, the outer wall of which is lower than the inner wall, means for supplying liquid fuel to the channel, a hollow plug, a sleeve screwed onto the plug and arranged to form a slot between itself and the said inner wall, said sleeve provided with an open-ended expansion-chamber into which said plug communicates above said slot, and means for supplying an expansive fluid to said hollow plug, and means for revolving said sleeve to vary said slot.

26. An atomizer-body having a channel in its top, the outer wall of which is lower than the inner wall, means for supplying liquid fuel to the channel, a hollow plug, a sleeve screwed onto the plug and arranged to form a slot between itself and the said inner wall, said sleeve provided with an open-ended expansion-chamber into which said plug communicates above said slot, means for supplying an expansive fluid to said hollow plug, means for revolving said sleeve to vary said slot, adjustable means for closing a portion of said slot, and means for adjusting said closure means.

27. An atomizer-body having a channel in its top, the outer wall of which is lower than the inner wall, means for supplying liquid fuel to the channel, a hollow plug, a sleeve screwed onto the plug and arranged to form a slot be-

tween itself and the said inner wall, said sleeve provided with an open-ended expansion-chamber into which said plug communicates above said slot, and means for supplying an expansive fluid to said hollow plug, means for revolving said sleeve to vary said slot, and a deflector above and spaced apart from said outer wall.

28. An atomizer-body having a channel in its top, the outer wall of which is lower than the inner wall, means for supplying liquid fuel to the channel, a hollow plug, a sleeve screwed onto the plug and arranged to form a slot between itself and the said inner wall, said sleeve provided with an open-ended expansion-chamber into which said plug communicates above said slot, means for supplying an expansive fluid to said hollow plug, means for revolving said sleeve to vary said slot, adjustable means for closing a portion of said slot, means for adjusting said closure means, and a deflector above and spaced apart from said outer wall.

29. An atomizer comprising a body having a curved or arc-shaped channel and a plane face outside said channel, and a plane face inside said channel, said inside plane face being higher than the rim of the outside plane face, means for supplying liquid fuel to said channel, means for discharging expansive liquid over said inside plane face and across and above said annular channel, adjustable means for closing said outer channel, means for operating said adjustable means to vary the width of the discharge, and an annular deflector above and spaced apart from said plane faces.

30. An atomizer comprising a body having a curved or arc-shaped channel and a plane face outside said channel, and a plane face inside said channel higher than the outside plane face, means for supplying liquid fuel to said channel, means for discharging expansive fluid over said inner plane face and across and above said channel, regulable means for closing said outer channel and for cutting off the discharge of expansive fluid over the corresponding portion of said inner face, means for operating said regulable means, and an annular deflector above and spaced apart from said plane faces.

31. An atomizer comprising a body having two discharge-slots, means for supplying oil through one of said slots, means for supplying expansive material through the other slot, said slots being so arranged that the fuel and fluid material intermingle outside said slots, adjustable means for closing said slots, means extending from said atomizer to within the reach of the operator whereby said closing means may be operated to simultaneously vary the discharge from said slots as desired, and an annular deflector arranged above and spaced apart from the outer discharge-slot.

32. A body having a curved or arc-shaped channel, means for supplying liquid fuel to

5 said channel, means for directing an expansive fluid across said channel, a two-part segmental member having a bead to fit a portion of said channel and to limit the space across which the expansive fluid may pass, and means 10 for moving the parts of said segmental member to vary the space across which the expansive fluid may pass, and a deflector arranged above and spaced apart from said annular 15 channel.

10 33. An atomizer comprising a body having an upwardly-opening curved or arc-shaped channel, means for supplying liquid fuel to said channel, means for directing an expansive material outward radially across said channel above the same, detachable means for closing a portion of said channel, means whereby said detachable means may be adjusted to regulate closure of said channel, and 20 a deflector arranged above and spaced apart from said annular channel.

20 34. An atomizer comprising a body having a downwardly-tapering channel, means for supplying liquid to said channel, means for discharging a fluid across said channel, a two-part adjustable member provided with a bead 25 adapted to close a part of said channel, and means for adjusting the parts of said member.

30 35. A burner comprising a body having a curved or arc-shaped channel, the outer wall of which terminates in a plane surface, means for supplying liquid fuel to said channel, means for directing an expansive fluid outward radially across said channel in a plane 35 parallel to said terminal plane, a deflector arranged above and spaced apart from said channel, means for closing a portion of said channel and adjustably controlling the direction of the outflowing product, and means for adjusting said means as desired.

40 36. An atomizer comprising a hollow body divided into two chambers and having a curved or arc-shaped channel, a hollow plug in communication with the inner chamber, said plug 45 provided with an externally-threaded shank, a sleeve threaded thereon, said sleeve embracing an open-ended chamber of greater diameter than the plug, the wall of said inner chamber and the end of said sleeve forming a slot 50 opening from said chamber, said plug provided with a port opening above the plane of the lower end of said sleeve, and an annular deflector surrounding said sleeve, the under 55 face of said deflector spaced apart from and lying above the rim of said body.

37. An atomizer comprising a curved or arc-shaped channel, means for supplying liquid fuel thereto, an expansion-chamber having an annular outlet adapted to emit expansive fluid 60 radially across said channel, means for supplying expansive fluid to said chamber, a segmental member closing a portion of said channel, and independent means for closing a portion of said annular outlet.

65 38. An atomizer comprising a curved or arc-

70 shaped channel, means for supplying liquid fuel thereto, a vertically-adjustable member above the inner wall of said channel, said member provided at its lower end with an open-ended expansion-chamber, a radial expansive fluid outlet formed between the lower end of said member and the edge of said inner wall, means for supplying expansive fluid to said chamber, means for closing a portion of said channel, and independent means extending up 75 within a portion of said chamber for closing the said outlet.

80 39. A liquid-hydrocarbon-burning apparatus comprising a body having two curved or arc-shaped channels, adjustable means arranged to close a portion of the outer channel and to limit the space across which the expansive fluid will pass, operating means extending outside the furnace or fire-box for adjusting said first-named means, a steam-supply 85 pipe operatively connected with the inner channel, an oil-supply pipe surrounding said steam-pipe and operatively connected with the outer channel, and an air pipe or cylinder surrounding said oil-supply pipe and opening below and at the front of the body.

90 40. A liquid-hydrocarbon-burning apparatus comprising a body having two curved or arc-shaped channels, adjustable means arranged to close a portion of the outer channel 95 and to limit the space across which the expansive fluid will pass, operating means extending outside the furnace or fire-box for adjusting said first-named means, a steam-supply pipe operatively connected with the inner 100 channel, an oil-supply pipe surrounding said steam-pipe and operatively connected with the outer channel, an air pipe or cylinder surrounding said oil-supply pipe and opening below and at the front of the body, and means 105 in connection with the outer end of said air-pipe for regulating the admission of air thereto.

110 41. A liquid-hydrocarbon-burning apparatus comprising a body having an upwardly-opening curved or arc-shaped channel, means for directing an expansive material outward radially across said channel above the same, detachable means for closing a portion of said channel, means for adjusting said detachable 115 means to regulate the closure, a steam-supply pipe connected with said expansive-material-directing means, an oil-supply pipe surrounding said steam-pipe, and operatively connected with said channel, and an air-pipe surrounding said oil-pipe and opening at the front and below said body.

120 42. A liquid-hydrocarbon-burning apparatus comprising a body having an upwardly-opening curved or arc-shaped channel, means for directing an expansive material outward radially across said channel above the same, detachable means for closing a portion of said channel, means for adjusting said detachable 125 means to regulate the closure, a steam-supply 130 pipe connected with said expansive-material-directing means, an oil-supply pipe surrounding said steam-pipe, and operatively connected with said channel, and an air-pipe surrounding said oil-pipe and opening at the front and below said body.

5 pipe connected with said expansive-material-directing means, an oil-supply pipe surrounding said steam-pipe, and operatively connected with said annular channel, an air-pipe surrounding said oil-pipe and opening at the front and below said body, and means at the outer end of said air-pipe for regulating the admission of air thereinto.

10 43. A hydrocarbon-burning apparatus comprising a body having a curved or arc-shaped channel and a plane face outside said channel, and a plane face inside said channel, said inside plane face being higher than the outside plane face, adjustable means for closing said outer channel, means extending outside the fire-box for operating said adjustable means to vary the width of the discharge, a steam-pipe connected with said body and adapted to discharge expansive fluid over said inside 15 plane face and across and above said channel, an oil-supply pipe surrounding said steam-pipe and operatively connected with said channel, and an air-pipe surrounding said oil-pipe and opening below said body and in front of the same.

20 44. An atomizer comprising a body having two curved or arc-shaped channels, means for supplying liquid fuel to the outer channel, means for supplying expansive fluid to the inner channel, a two-part segmental ring arranged to close a portion of the outer channel and to limit the space across which the expansive fluid may pass, said two-part segmental ring provided with gear-teeth, and an operating-rod extending beyond the atomizer and provided at its inner end with a gear meshing with the gear of said segmental ring.

25 45. An atomizer comprising a body having two curved or arc-shaped channels, means for supplying liquid fuel to the outer channel, means for supplying expansive fluid to the inner channel, a two-part segmental ring arranged to close a portion of the outer channel and to limit the space across which the expansive fluid may flow, said two-part segmental ring provided with gear-teeth, an operating-rod extending beyond the atomizer and provided at its inner end with a gear meshing

30 with the gear of said segmental ring, and a secondary segmental ring in connection with said two-part ring for closing the inner channel when said two-part ring is operated to adjust the width of the flame.

46. An atomizer comprising a body having a curved or arc-shaped channel, means for supplying liquid fuel thereto, means for discharging expansive fluid across said annular channel, a two-part segmental ring arranged to close a portion of said channel and to limit the space across which the expansive fluid 35 may pass, said two-part segmental ring provided with gear-teeth and an operating-rod extending beyond the atomizer and provided at its inner end with a gear meshing with the gear of said segmental ring. 65

47. An atomizer comprising a body having a curved or arc-shaped channel, means for supplying liquid fuel thereto, means for discharging expansive fluid across said channel, a two-part segmental ring arranged to close a portion of said channel and to limit the space 40 across which the expansive fluid may flow, and means for regulating the parts of said ring to vary said space. 7c

48. An atomizer comprising a body having a curved or arc-shaped channel, means for supplying liquid fuel thereto, means for discharging an expansive fluid across said channel, a two-part segmental ring arranged to close a portion of the outer channel and to 45 limit the space across which the expansive fluid may pass, means for regulating and adjusting the parts of said ring to vary said space, and, means for closing said channel at the rear and between the rear ends of said 50 parts of said ring. 80

In testimony whereof I have signed my name to this specification, in the presence of two subscribing witnesses, at Los Angeles, in the county of Los Angeles and State of California, 90 this 30th day of November, 1903.

ALLAN C. RUSH.

Witnesses:

FREDERICK D. LYON,
JULIA TOWNSEND.
